UNITED STATES PATENT OFFICE.

JOHN KRALUND, OF BROOKLYN, NEW YORK, ASSIGNOR TO DOEHLER DIE CASTING COMPANY, OF BROOKLYN, NEW YORK, A CORPORATION OF NEW YORK.

DIE-CASTING APPARATUS.

1,299,738.

Specification of Letters Patent. Patented Apr. 8, 1919.

Application filed July 17, 1918. Serial No. 245,263.

To all whom it may concern:

Be it known that I, JOHN KRALUND, a citizen of the United States, residing in the borough of Brooklyn, county of Kings, and State of New York, have invented certain new and useful Improvements in Die-Casting Apparatus, of which the following is a specification.

My invention relates to die casting apparatus and particularly to improvements in the mechanism for supplying molten metal from a melting pot to a suitable die or mold by air pressure. By my invention, a swinging or otherwise movable member, which may be termed a carrier or a ladle, is made use of, this device dipping into the molten metal in the melting pot, so that a charge of the same runs into its interior after which the carrier is moved to cause its mouth to align accurately with the gate or opening of the die. As soon as this is accomplished, compressed air is forced through the carrier to deliver the charge of metal into the die. By mechanism of this character, the charge is forced into the die accurately and efficiently, while at the same time only the metal in the swinging carrier device is exposed to the air pressure, so that the oxidation of the main body of metal in the melting pot by the use of the air pressure is prevented.

My invention provides improved mechanism for the operation of devices of this character for the purpose of insuring accuracy and certainty of operation as well as simplicity of construction and speed in operation. My improved mechanism is so mounted as to cause the mouth of the carrier device to first be submerged in the molten metal in the melting pot to take a charge, after which the carrier device moves to lift the mouth thereof out of the metal and above the melting pot, the mouth-piece being projected into engagement with the gate of the die which is mounted immediately above the edge of the melting pot. The carrier device is so mounted as to accurately align the mouth-piece thereof with the opening of the die member, and the carrier device is positively held or locked in this engaging position while the charge of molten metal is forced therefrom into the die. My invention also provides various improved features of construction, including the use

of removable mouth-pieces for the carrier device, which may be readily replaced and secured in position, and the use of a movable device for breaking the bond between the mouth-piece of the carrier and the gate member with which it engages, whenever any such bond tends to form, or to permit the removal of the gate member for cleaning.

In order that a clearer understanding of my invention may be had, attention is hereby directed to the accompanying drawings forming part of this application and illustrating a preferred embodiment of my invention. In the drawings, Figure 1 represents a side elevation of casting apparatus embodying my invention, certain parts being shown in section; and Fig. 2 is an enlarged side elevation of the melting pot and adjacent parts, certain parts being shown in section.

In the construction shown in the drawings, the melting pot 1 is adapted to contain the main body of molten metal and is heated by any usual heating means (not shown) in the heating chamber 2. The swinging carrier or ladle 3 is shown in Fig. 2 in the full line position, in which it is adapted to deliver a charge of molten metal into the die. This figure also indicates in dotted lines the opposite position of the carrier in which the charge is taken into the same. The carrier is provided with a hollow interior, comprising a central bore 4, terminating at the forward end in a mouth 5 in which the removable mouth-piece 6 may be fitted, this mouth-piece having a tapering passageway 7 therethrough aligned with the bore of the carrier device. The carrier may be of any suitable shape, such as that shown, and is closed at the rear as by the closure 8, through which extends a flexible pipe connection 9 for the introduction of compressed air.

The carrier is supported by means enabling the mouth-piece 6 to be submerged within the molten metal in the container 1 in position to permit the molten metal to readily flow into the same. The supporting means are also designed to raise the mouth-piece entirely above the melting pot or container 1 and project the same laterally of the pot into alignment with the gate member of the die which may be located immediately above the edge of the melting pot.

This may be accomplished by provisions for pivotally supporting the carrier device, together with other provisions for moving the device bodily across the melting pot into position to aline the mouth of the carrier device with the die opening.

In the preferred embodiment of my construction as illustrated, the mouth or forward end of the carrier device is supported

- 5 by a pair of swinging arms, one of which is illustrated at 10. Only one of these arms is shown, the construction being the same on both sides of the device. The arm shown is pivotally mounted at its lower end on a horizontal pin 11 carried by a bracket 12 which extends upwardly from the upper edge of one of the side frame members 13 of the frame inclosing the heating chamber 2, within which the molten metal container 1 is secured. An arm similar to the arm 10 may be similarly mounted on the opposite side of the apparatus. The upper ends of the arms 10 are connected by a horizontal pin 14, which is rotatably mounted in the boss 15 formed on a web 16 extending upwardly from the forward portion of the carrier device 3, or alined pins 14 may be used, rotatably mounted in parallel webs 16. The arms 10 are adapted to swing from their lower rearwardly inclined position, in which the mouth piece 6 is submerged within the molten metal, as is shown in dotted lines in Fig. 2, to the forward position, in which arms 10 stand substantially vertically above their pivots 11 in which the mouth-piece 6 is raised above the edge of the melting pot.

In the construction shown in the drawings, the carrier device 3 is provided with a rearwardly extending bracket 17. A pair of arms, one of which is shown at 18, are pivotally mounted at their upper ends on pins, one of which is shown at 19, carried by a pair of upwardly extending brackets or pedestals rising from the opposite side frame members 13 of the apparatus, one of these brackets being shown at 20. Arms 18 carry at their lower ends a rod 21, which is journaled in the lug 17 of the carrier device 3, arms 18 being adapted to swing from the dotted line position, in which the mouth-piece 6 is submerged, to the full line position shown in Fig. 2 in which the mouth-piece is raised and projected forwardly above the edge of the melting pot. It will, of course, be understood that either one or two of the arms 10 and 18 may be used as desired, and one or two of the lugs 17 and rods or pins 21.

My invention also preferably includes mechanism for forcing the mouth-piece 6 positively into engagement with the gate opening of the die with a desired pressure and holding it in such position positively while the charge is being forced into the die. 65 This may effectively be provided by the tog-

gle construction shown in the drawings, in which the arm 22 is pivotally mounted on the shaft 23 carried by the frame 13 of the structure. A hand lever 24 is also secured to shaft 23 to operate the device. The other 70 member of the toggle consists of an arm 25 which is pivotally secured at 26 to the arm 22, the other end of arm 25 being rotatably secured to the pin 21 mounted in lug 17 of the carrier device 3. The arm 22 is provided 75 with a flange 27 extending above arm 25, a set screw 28 extending through flange 27 into contact with the upper surface of arm 25, this set screw constituting a stop for determining the position of the carrier device 80 in which the charge is to be forced into the die member. It will, of course, be understood that the arms 22 and 25 may be and preferably are duplicated, one complete toggle being used on each side of the machine 85 in connection with one of the arms 18.

The die member may be positioned relative to the melting pot and separated therefrom to remove the finished casting at each operation by any desired means. In the device 90 illustrated in the drawings, a frame represented generally by the reference character 29 is mounted on a standard or standards 30 which may be moved along the track or tracks 31 into adjusted position and there 95 secured. Frame 29 is provided with forwardly extending rods 32, to the forward end of which is secured the gate member 33 which has a horizontal opening extending therethrough provided with a removable 100 bushing or gate former 34. The end of this bushing extends somewhat beyond the member 33 and is provided with a tapered mouth, as shown at 35, with which the tapered mouth-piece 6 is adapted to engage. The 105 frame 29 may be adjusted into position until the member 33 engages the upwardly extending portions 36 of the brackets 12.

The frame 29 is provided with an upwardly extending portion or portions 37, in 110 which is rotatably mounted the shaft 38, carrying a pinion 39 and rotated by means of the hand wheel 40. Rotation of the hand wheel reciprocates the rack 41 which operates the ram member 43, to which one portion of the die may be secured. Preferably the connection for operating ram member 43 comprises links 42, 42, which are pivotally connected at their inner ends to rack 41, and at their outer ends to the pivotal 115 connections between links 42^a and 42^b, links 42^a being pivoted at their forward ends to ram member 43, and links 42^b being pivoted at their rear ends to frame 29. Links 42^a and 42^b act as toggles, as shown, to lock ram 125 member 43 in the forward position shown in which the die is closed. I do not claim this mechanism herein, a similar mechanism being disclosed and claimed in application of John Kralund, Clarence Duckworth and 130

Marcus Stern, Serial No. 261,972, casting apparatus, filed November 11, 1918.

- The mouth-piece member 6 is preferably removable, as stated, and may be secured 5 within the mouth 5 of the carrier device by any convenient means permitting its ready replacement. As is indicated in the drawings, the carrier device is provided with forwardly extending lugs 44, between which 10 the lugs 45 on the mouth-piece may be slipped, the mouth-piece being secured in position by a partial rotation after it has been mounted within the lugs 44, this partial rotation locking the mouth-piece in position 15 because of the wedging engagement of the inclined surfaces indicated on lugs 45 within their seats in lugs 44. The bushing 34 should also be replaceable and may be mounted in 20 position in member 33 with a sliding fit. The object of making the mouth-piece and bushing 25 34 removable is to enable the same to be replaced or cleaned when they have been sufficiently worn away or coated by the action of the molten metal thereon. The mouth-piece and bushing are formed of suitable metal.
- A lever 46 is preferably mounted upon the mouth portion 35 of bushing 34 to rotate therewith, the lever being provided with a 30 sleeve portion 47 fixedly seated on the bushing. This lever may be oscillated in a vertical plane about the axis of bushing 34 whenever there is any tendency for the molten metal to form a bond between mouth-piece 35 and the mouth 35 of bushing 34, this oscillation of the lever effectively breaking such bond. A splash guard 48 may be mounted over the forward end of carrier 35 to prevent the splashing of molten metal.
- It will be noted that the pressure with 40 which mouth-piece 6 is forced against its seat 35 is regulated by adjusting the set screw 28 and that the mouth-piece is held positively and in proper alignment with the mouth 35 of bushing 34, while the charge of molten metal in the bore 4 of carrier device 3 is forced by the compressed air into the die. The lever 46 may, if desired, be used 45 as a handle for the easy removal of the gate former or bushing 34 whenever it is desired to clean the latter, and a clip or latch 46' may be mounted on member 33, to removably extend about and hold lever 46, to prevent the gate former being pulled out by adhesion to mouth-piece 6.

What I claim is:—

1. In casting apparatus, the combination of a molten metal container, a carrier device having a hollow interior and a mouth communicating therewith, supporting connections pivotally secured to the forward and rear portions of said carrier device, arranged to be moved to cause said mouth to be submerged within the molten metal in said container, at one limit of movement, and to cause said mouth to be raised above and projected over the top of said container, at the other limit of movement, and connections for carrying compressed air into said carrier device, to discharge molten metal from 70 the mouth thereof into a die.
2. In casting apparatus, the combination of a molten metal container, a carrier device having a hollow interior, a mouth at the forward end and a compressed air connection 75 at the rear, a swinging arm pivotally secured to said container at one end and to the forward portion of said carrier device at the other end, positioned to support said mouth within the container in one position 80 and above and beyond the container in another position, and swing supporting means pivotally secured to the rear portion of the carrier device.
3. In casting apparatus, the combination 85 of a molten metal container, a carrier device having a hollow interior, a mouth at the forward end and a compressed air connection at the rear, and means for supporting said device, and swinging and moving the same 90 bodily laterally of the container, such that said mouth will be submerged within the molten metal in the container in one position, and will be projected horizontally above the edge of said container in another position 95 for registration with a die opening.
4. In casting apparatus, the combination 100 of a molten metal container, a carrier device having a hollow interior, a mouth at the forward end and a compressed air connection at the rear, said device having a web portion extending vertically above its forward end, an arm pivoted at its lower end to said container and at its upper end to the forward part of said web portion, said arm being 105 adapted to swing from a vertical position in which said mouth is above the edge of the container to a lower rearwardly extending position in which said mouth is within the container, and means supporting the 110 rear portion of said device from the container, adapted to move said device forward and back in a plane parallel to that in which said arm swings.
5. In casting apparatus, the combination 115 of a molten metal container, a carrier device having a hollow interior, a mouth at its forward end and a compressed air connection at the rear, an arm pivotally connected to a fixed point and to said device for supporting the same and raising and lowering said mouth out of and into the molten metal in said container, and an arm secured to a different point on said device for supporting the same and moving it forward and back as 125 said first arm raises and lowers said mouth.
6. In casting apparatus, the combination 130 of a molten metal container, a carrier device having a hollow interior, a mouth at its forward end and a compressed air connec-

tion at the rear, an arm pivotally connected to a fixed point and to said device for supporting the same and raising and lowering said mouth out of and into the molten metal 5 in said container, an arm pivotally secured to the rear portion of said device and to a fixed point, and a toggle pivotally secured to said last named arm for swinging the latter and holding it in forward position, in which 10 said mouth is raised.

7. In casting apparatus, the combination of a molten metal container, a carrier device having a hollow interior, a mouth at its forward end and a compressed air connection at the rear, means for supporting said device, means for moving it forward and back and locking it in forward position, said mouth being adapted to dip into said container as it moves back, and means for 20 raising said mouth and alining it with a desired point as said device moves forward.

8. In casting apparatus, the combination of a molten metal container, a carrier device having a hollow interior, a mouth at its 25 forward end and a compressed air connection at the rear, means for supporting said device, means for moving it forward and back and locking it in forward position, comprising a toggle, and means for raising 30 said mouth from a point within said container, as said device moves forward, into position to aline with a die opening.

9. In casting apparatus, the combination

of a molten metal container, a carrier device having a hollow interior, a mouth at its forward end and a compressed air connection at the rear, a tapering mouthpiece removably secured in said mouth, a gate member having a horizontal opening therethrough above said container, and means for supporting and moving said device to cause said mouthpiece to be submerged in molten metal in said container in one position, and to extend into said opening, in alinement therewith, in another position.

10. In casting apparatus, the combination of a molten metal container, a carrier device having a hollow interior, a mouth at its forward end and a compressed air connection at the rear, a gate member having a horizontal opening therethrough above said container, a bushing movably mounted in said opening and extending beyond the same, toward said carrier device, a lever having a boss fixedly seated on the extended portion of said bushing, and means for supporting and moving said device to carry said mouth from the interior of said container into the end of said bushing and vice versa.

This specification signed and witnessed this 9th day of July, 1918.

JOHN KRALUND.
